UNITED STATES PATENT OFFICE

GAILLARD E. WEAVER AND ALBERT J. VETTEL, OF SPRINGFIELD, ILLINOIS, ASSIGNEES
TO WEAVER MANUFACTURING COMPANY, OF SPRINGFIELD, ILLINOIS, A CORPO-
RATION OF ILLINOIS

JACK

Application filed May 26, 1928. Serial No. 280,812.

Our invention pertains to or concerns jacks, or load raising and lowering appliances, such as are commonly used in garages and elsewhere in connection with motor-vehicles, its leading aim and object being the provision of improved and novel means for controlling the pawls or dogs, or their equivalents, of the elevating and lowering ratchet-mechanism and for raising the load-engaging member or saddle quickly initially without resort or recourse to the slower, but more powerful, step-by-step ratchet-mechanism.

To permit those acquainted with this industry to completely understand the invention, a present, desirable embodiment of the same has been illustrated in the accompanying drawings, which form a part of this specification, and throughout the views of which identical reference numerals have been used to designate the same parts of the mechanism.

In the drawings,—

Fig. 1 is a longitudinal section through the improved jack just inside of one of the side members of the frame, on line 1—1 of Fig. 2, the parts of the appliance being shown in condition for raising the load-engaging saddle intermittently by the pawl and ratchet mechanism;

Fig. 2 is a broken plan view of the complete construction;

Fig. 3 is a view similar to Fig. 1, illustrating the load-saddle during its quick, preliminary elevating action; and

Fig. 4 is a view similar to Fig. 1, showing the parts in condition for lowering the load step by step.

Referring to these drawings, it will be seen that the improved and novel jack comprises a suitable frame including two side elements 11, 11 suitably spaced apart, the forward end of the frame being equipped with a transverse axle 12 supplied with suitable carrying-wheels 13, 13 adapted to roll on the floor or ground, the other ends of such side frame members having feet 14 designed to rest on the ground during the load raising and lowering operation and to be raised so that the jack as a whole may be wheeled

around to any desired location on the wheels 13, 13.

A ratchet-sector 15 is rockingly mounted at 16 between the frame side elements 11, 11, and it has an extension arm 17 to which a load saddle or seat 18 is hinged at 19, substantial horizontality of the top face of such seat being maintained at all times by a link 21 hinged to the saddle at 22 and to the main frame at 23.

A bifurcated operating-handle 24 is fulcrumed on the frame at 25 between its side members, and such handle is located below a pair of lugs 26, 26 extended inwardly or toward, and in register with, one another, so that when the handle is rocked up or lifted an unusual or excessive amount, it will contact with the under sides of such projections and raise the feet 14 of the frame off of the floor, thus permitting the jack to be rolled away on its wheels 13, 13 as may be required and permitting its ready application in proper position preliminary to the load-elevating operation.

Near its fulcrumed end, handle 24 has a depending extension or bracket 27 to which a lifting power pawl or dog 28, adapted to co-operate with the teeth or notches of the ratchet-sector, is fulcrumed at 29, the pawl being normally pulled up to its work by a coiled spring 31 fastened at one end to the handle, at 32, and secured at its other end to a short tail 33 of the pawl.

As is customary in structures of this general character, a second, locking or holding pawl or dog 34, also designed and arranged to coact with the ratchet-sector, is hinged on the frame at 35, and is pulled up to its work by a coiled spring 36 connected thereto and to the jack-frame in any appropriate or convenient manner.

In order that the pair of pawls may be caused to operate in the intended manner to perform their usual functions, a suitably-shaped cam 37 is hinged or fulcrumed at 38 on the inner side of one of the frame parts 11, such cam having an upstanding projection or finger 39, and the two pawls have lateral or side pins 41 and 42, respectively, below the lower, cam-edge surface of the part 37.

A bell-crank lever, characterized as a whole 43, is rockingly mounted on the fulcrum-shaft 16 of the ratchet-sector and it is supplied with a spring 40 connected thereto and to the frame, which tends to rock it in a counter-clockwise direction as the parts are viewed in Figs. 1, 3 and 4, one arm 44 of such bell-crank lever having a side projection or lug 45 adapted selectively to co-operate with the adjacent, top marginal-flange 46 of the arm 17 (see Fig. 3) to preliminarily, rapidly raise the saddle 18 substantially to load-contacting elevation, or to bear on the edge of finger 39 (see Fig. 4) to operate cam 37 during the descent of the load, the other arm 46 of the bell-crank lever having its end pivotally joined at 47 to an end of a rod 48, whose other end is threaded into a connector 49, a lock-nut 51 being provided to prevent unintentional loosening of the elements.

Such connector or joining member 49 has two ribs 52 and 53 on its under side, affording aligned bearings to slidably accommodate an end portion of a companion, bent rod 54, the other end of which is hinged or pivoted at 55 to a bent handle 56 fulcrumed on the main operating-handle 24 at 57, and projecting down below such handle, as is clearly illustrated.

That portion of rod 54 in the connector 49 has a cross-pin 58 extended therethrough and projecting therefrom, a coiled spring 59 encircling the rod and bearing at its opposite ends against the pin and the bearing lug 52, whereby the adjacent end face of the rod is normally kept pressed against an abutment or stop 61 forming part of the housing 49.

The appliance is operated practically as follows:

Assuming that the jack has been rolled into proper position to locate the saddle or seat 18 correctly beneath the load, such as the axle of an automobile, the operator, while holding the handle 24 at any convenient location, rocks the handle 56 down, as shown in Fig. 3, and, by so doing, owing to the direct contact between the parts 54 and 61, the bell-crank lever arm 44 is positively swung upwardly, and its side pin 45, by engagement with the under surface of the flange 46, swings the arm 17 upwardly quickly and easily, and, of course, at the same time, the saddle is elevated until it reaches the load, without resort to the slower ratchet and pawl mechanism, which during this action is idle, the pawls uselessly or ineffectually riding over the ratchet-sector teeth.

As soon as the specified result has been accomplished, the workman releases handle 56, and, under the action of spring 40, the bell-crank lever and the handle automatically return to their initial or neutral position, as depicted in Fig. 1, in which relation of the parts the appliance is ready, by the upward and downward pumping action on handle 24,

to raise the saddle and load through the ratchet and pawl mechanism, step by step, in the ordinary way.

Such natural or ordinary position of the bell-crank lever and the auxiliary handle 56 is determined by the direction of pull of the spring 40, its points of attachment to the bell-crank lever and to the frame being such as to naturally restore the parts to the locations presented in Fig. 1.

With the elements in this relation, the operator swings the handle 24 up and down without grasping the handle 56, and the saddle and load are raised by the powerful ratchet-and-pawl step-by-step device in the usual way.

When it is desired to lower the load, the workman grasps the two handles 24 and 56 together, as shown in Fig. 4, and, while they are maintained in this relation, he rocks the handle 24 up and down, and the load and saddle are allowed to descend step by step, the cam 37, during that action, being kept in proper relation to the two pawls by the engagement of the bell-crank arm 44 with the cam projection 39.

During such operation, the spring 59 is maintained somewhat compressed, the movements of handle 24 permitting the bell-crank and the cam to shift sufficiently, during the load-lowering operation, to allow the pawls to correctly perform their functions.

The invention, as defined by the following claims, is susceptible of a variety of embodiments in satisfactory form, and, therefore, it is not limited or restricted to the details of structure herein presented.

We claim:

1. In a jack, the combination of a frame, a relatively slow-acting but powerful means on said frame to raise and lower the load, an operating-handle fulcrumed on said frame to actuate said means, an auxiliary-handle fulcrumed on said operating-handle, and means worked by said auxiliary-handle to operate said first-mentioned means to rise to the load comparatively quickly while its slow-acting elements are idle and to render said slow-acting means operative to enable said operating-handle to lower the load.

2. In a jack, the combination of a frame, a ratchet-sector fulcrumed on said frame, a load-engaging saddle, means connecting said sector and saddle whereby the rocking of the former will raise or lower the latter, an operating-handle fulcrumed on said frame, a spring-pressed lifting pawl fulcrumed on said handle and co-operating with said sector, a spring-pressed holding pawl for said sector fulcrumed on said frame, a cam hinged on said frame controlling the operation of said pawls, an auxiliary-handle fulcrumed on said operating-handle, a spring-pressed bell-crank lever fulcrumed on said frame and arranged to rock said sector and to coact with

5 said cam to render it active on said pawls, and a divided link connecting said auxiliary-handle and said bell-crank lever including a connector between the link parts yieldably extensible in one direction and forming a 10 rigid connection between the link sections in the other direction whereby said auxiliary-handle when rocked in one direction positively actuates said sector through said bell-crank lever to raise said saddle while the 15 pawls are idle and when rocked in the other direction render said cam operative on said pawls during the descent of the saddle and load, said auxiliary-handle when in its normal position allowing said pawls to be operative to raise the saddle and load step by step.

3. In a jack, the combination of a frame, a ratchet-sector fulcrumed on said frame, a 20 load-engaging saddle, means connecting said ratchet-sector and saddle whereby the rocking of the former will raise or lower the latter, an operating-handle fulcrumed on said frame, a lifting pawl co-operating with and 25 adapted to rock said ratchet-sector and actuated by said handle, a holding pawl for said ratchet-sector fulcrumed on said frame, cam means on said frame controlling the operation of said pawls, an auxiliary-handle ful- 30 crumed on said operating-handle, and means operated by said auxiliary-handle to raise said saddle initially quickly and to co-operate with said cam means to render it operative on said pawls during the lowering of 35 the saddle and its load.

4. In a jack, the combination of a frame, a relatively slow-acting powerful means on said frame to raise and lower the load, an operating handle therefor movably mounted 40 on said frame, an auxiliary-handle movably mounted on said operating-handle, and means worked by said auxiliary-handle to operate said first mentioned means to rise to the load comparatively quickly while its slow- 45 acting elements are idle and to render said slow-acting means operative to enable said operating-handle to lower the load.

5. In a jack, the combination of a frame, an operating-handle movably mounted on 50 said frame, a relatively slow-acting powerful means on said frame actuated by said handle to raise the load, an auxiliary-handle movably mounted on said operating-handle, means to cause said auxiliary-handle, when 55 permitted to do so by the operator, to assume automatically a normal position with relation to said operating-handle in which said powerful means is operative to raise the load slowly upon actuation of said operating-handle, means operated by said auxiliary-handle 60 when the latter is moved from said normal position to cause said load-raising means to rise to the load quickly while its slow-acting elements are functionally idle, and means 65 operated by said auxiliary-handle when the

latter is moved otherwise from said normal position to allow said operating-handle to lower the load gradually by said slow-acting means.

6. In a jack, the combination of a frame, 70 an operating-handle fulcrumed on said frame, a relatively slow-acting powerful means on said frame actuated by said handle to raise the load including a load-engaging saddle, an oscillatory sector fulcrumed on 75 said frame and lifting and holding pawls co-acting with said sector, an auxiliary-handle fulcrumed on said operating-handle, means to cause said auxiliary-handle, when permitted to do so by the operator, to assume 80 automatically a normal position with relation to said operating-handle in which said pawls are operative to raise said saddle step-by-step by said operating-handle, means operated by said auxiliary-handle when the latter is moved from said normal position to cause said saddle to raise quickly initially to engage the load while said pawls are functionally idle, and a cam actuated by said auxiliary-handle when shifted otherwise from 85 said normal position to cooperate with said pawls to permit the step-by-step descent of the load upon actuation of said operating-handle.

In witness whereof we have hereunto set 90 our hands.
